UNITED STATES PATENT OFFICE.

PIERRE LORILLARD, OF TUXEDO PARK, NEW YORK.

CONVEYER.

1,315,945.

Specification of Letters Patent. Patented Feb. 13, 1917.

Application filed April 16, 1907, Serial No. 368,462. Renewed July 19, 1916. Serial No. 110,210.

To all whom it may concern:

Be it known that I, PIERRE LORILLARD, a citizen of the United States, and a resident of Tuxedo Park, in the county of 5 Orange and State of New York, have invented certain new and useful Improvements in Conveyers, of which the following is a specification.

This invention relates to that type of conveying apparatus which is capable of continuous operation in a given direction, being particularly intended to provide an apparatus of this character which may be employed to advantage in situations where a 10 conveyer of more than ordinary length is required. A conveying apparatus constructed in accordance with my invention is characterized by the division of the complete apparatus into two or more distinct 15 portions or lengths arranged in series, end to end, and overlapped or otherwise constructed and arranged at their ends in such manner as to provide for the automatic transference of the load from the end of 20 one portion of the apparatus to the adjacent end of the next portion, each of these 25 portions constituting what may be termed a conveying unit, that is to say, a conveyer of limited length which is complete in itself 30 in that it is capable of operation independently of the remaining portion or portions. Each of these conveying units may have any desired length, within practical limits 35 of construction, and as many of them may be employed in series as may be desired, according to the requirements of the situation in which the apparatus is to be used. They may also be of any suitable construction, so long as they are adapted to provide 40 collectively a continuous conveyer extending between the two points to be connected by the apparatus, and in connection therewith I provide means for operating the several conveying units in such manner as to 45 secure a number of useful results, as will hereinafter appear.

In the accompanying drawings,—

Figure 1 is a side elevation of a portion of a conveying apparatus constructed in accordance with my invention;

Fig. 2 is a diagrammatic plan view of the top portion of the same;

Fig. 3 is a longitudinal section, on an enlarged scale, through a portion of the apparatus shown in Fig. 1;

Fig. 4 is a plan view, partly in section

and with certain parts broken away, of the parts shown in Fig. 3;

Fig. 5 is a cross section on the line $x-x$ in Fig. 1;

Figs. 6, 7 and 8 are diagrammatic views illustrating certain arrangements hereinafter described for controlling the operation of the apparatus, and

Fig. 9 is a partly-diagrammatic view 65 illustrating another arrangement of the apparatus.

In Figs. 1 and 2 of the drawings is shown a complete conveying unit adapted for transferring freight, baggage or the like in 70 a horizontal direction, together with the adjacent end portion of another conveying unit which forms the next unit of the series constituting the complete apparatus. This series will ordinarily comprise a considerable number of conveying units, but for the sake of clearness of illustration no other units of the series are shown in these figures, as the construction of each of the units 75 will or may be precisely similar to that of the complete unit illustrated, so that the description of the latter will apply to each of the others.

As preferably constructed, each of these conveying units comprises a number of parallel and laterally-adjacent conveyer sections arranged in sets, the sections of each set being interleaved between the other sections and providing collectively a supporting surface for the load, and the sets of sections being so operated that their supporting surfaces are exposed above one another in sequence and given a limited forward movement in the direction of conveyance while so exposed, followed by a return 85 movement along a relatively depressed path, so that the sets of sections are successively operative for conveyance and are conjointly effective to transport a load continuously in a predetermined direction from 90 one end of the conveying unit to the other. A conveyer of this type is shown and described in U. S. Letters Patent No. 807,564, granted to me on the 19th day of December, 1905, to which reference may be had for a 105 full understanding of the principles involved therein.

Referring to Fig. 2 of the drawings, the letters A and B indicate a number of similar conveyer sections, each of which extends 110 horizontally from one end of the conveying unit to the other, or substantially so. These

sections are located side by side, parallel with one another, and are arranged in two sets, the sections A forming one set and the sections B forming the other set. Said sections A and B alternate in lateral arrangement, so that the sections of each set are interleaved between those of the other set, and as many of them are employed as are required to give the conveyer the desired width, the upper edges of the sections of each set being located in the same plane and near enough together to provide collectively a supporting surface which will be sufficiently continuous to support whatever is intended to be conveyed. The details of the particular construction illustrated are shown in Figs. 3 and 5, according to which each of the sections A is composed of a double line of flat strips 2 riveted or otherwise secured to opposite vertical faces of the upper portions of a number of supporting posts 4 and resting at their lower edges on shoulders 6 formed on said posts. Each of these posts is located in transverse alinement with the corresponding posts for the other sections A and rests upon and is bolted to the upper edge of a cross beam 8, being recessed at its lower end to embrace the same, as shown in Fig. 3. There are thus as many cross beams 8 as there are transverse lines of posts 4, and all these cross beams are supported on and rigidly secured to a pair of longitudinally-extending T beams 10. In a precisely similar manner the conveyer sections B are each composed of a double line of strips 3 secured to posts 5 having supporting shoulders 7 and otherwise constructed and arranged like the posts 4, said posts 5 being supported on and bolted to cross beams 9 which are carried by and secured to a pair of longitudinally-extending T beams 11 located between the beams 10. All the conveyer sections of each set are thus rigidly connected and combined to form a unitary structure or element. The spacing of the posts which carry the conveyer sections is such as to permit the sections of each set to move freely between those of the other set, in parallelism therewith, and the cross beams 8 and 9 are located at a sufficient distance apart in the direction of the length of the conveyer to permit the relative longitudinal movements thereof which are herein-after described. Said cross beams are also sufficiently elevated above the top surfaces of the T beams which carry them, as by means of downwardly-extending supporting portions 12 and 13 respectively, to permit said T beams to have the relative up-and-down movements which the operation of the apparatus requires without bringing either pair of T beams into contact with the cross beams which are carried by the other pair.

5 The relative movements of the two sets of

conveyer sections which render them operative for conveying purposes are preferably provided for as follows. The T beams 10 are supported and adapted to run longitudinally on grooved rollers 14 carried respectively by rock arms 15, a pair of said rollers and rock arms being provided for each T beam and located at suitable points to distribute the weight of the parts carried thereby. Each rock arm 15 is provided at its lower end with a sleeve 16 mounted to turn on a transversely-extending rock shaft 17, and the rock arms corresponding to each T beam are connected by a jointed link 18 to which is pivoted the upper end of an arm 19 pivotally mounted at its lower end on a rock shaft 20. Each arm 19 is provided with a roller 21, Fig. 4, adapted to bear on the edge or cam face of a cam 22 secured to a shaft 23, which serves as the driving shaft, the cam faces of the two cams 22 being identical in contour and in operative relation to their rollers 21. In like manner, the T beams 11 are supported for longitudinal reciprocation on four rollers 24 carried respectively by rock arms 25 which are secured at their lower ends to the corresponding rock shafts 17 and connected in pairs by links 26, each link being pivoted to the upper end of an arm 27 which is secured at its lower end to the rock shaft 20 and is provided with a roller 28 adapted to bear on the edge of a cam 29 secured to the driving shaft 23, the two cams 29, like the two cams 22, being identical in contour and in operative relation to their rollers. The arrangement of the parts above described is such that all the rock arms 15 are parallel with one another, this parallelism being maintained in all positions of the rock arms 15 by pivoting the links 18 thereto at equal distances from the corresponding rock shafts 17. All the rollers 14 are also located at the same distance from said rock shafts, and the rock arms which carry said rollers are inclined somewhat from a vertical position, as shown in Fig. 3, so that they tend to swing downward under the weight of the parts carried by the rollers 14 and thus to hold the rollers 21 in contact with the corresponding cams 22. Similarly, the rock arms 25 are arranged in parallel relation to one another and so maintained by the links 26, and are also inclined like the rock arms 15, for the same reason and with the same result. It follows from this arrangement that the rotation of the driving shaft 23 will cause the T beams 10 and 11 to rise and fall according to the contour of the cams 22 and 29, while the upper edges of the conveyer sections A and B which are carried by and move with said T beams respectively will be kept parallel with one another and with the horizontal direction of conveyance in all positions of said sections.

The T beams 10 and 11 are reciprocated longitudinally on their respective supporting rollers by suitable means, as best illustrated in Fig. 3 in connection with the T beams 11. According to the construction shown in this figure, each of said T beams 11 is reciprocated on its rollers 24 by means of an arm 35 secured at its lower end to a rock shaft 31 and notched at its upper end 10 to receive a laterally-projecting pin 36 carried by the corresponding T beam 11. There are two of these arms 35, one for each T beam, and each arm is located at one side of an adjacent cam 29 and is provided with a 15 pin or roller 37 arranged to travel in a cam groove 38 cut in one face of said cam, the two cam grooves 38 being duplicates of each other and operating in unison. The parts employed for reciprocating the T beams 10 20 on the rollers 14 are duplicates of those just described, and comprise two similar arms 30 each pivotally mounted at its lower end on the rock shaft 31 and notched at its upper end to receive a pin 32 carried by the corresponding T beam 10, and also provided with a pin or roller 33 arranged to travel in a cam groove 34 cut in one face of the adjacent cam 22, the two cam grooves 34, like the cam grooves 38, being duplicates of each 25 other. The transversely-extending rock shafts 17, 20 and 31, as well as the driving shaft 23, are journaled at their ends in suitable bearings carried by a stationary framework herein represented as consisting of 30 longitudinally-extending side beams 39 supported at intervals on cross beams 40 which in turn may rest upon any suitable foundation.

The parts above described are so proportioned and the several cams and cam grooves are so cut and timed that upon the rotation of the driving shaft 23 each set of conveyer sections in turn will be raised to its position of maximum elevation and given a longitudinal movement forwardly or in the direction of conveyance along the rollers which support it, at or near the end of which forward movement it will be depressed and then moved back to its first position, the forward movement of each set of sections being concurrent with the return movement of the other set. Both sets of conveyer sections thus move in like direction along similar closed paths, the flat upper portions of 55 which are so determined as to cause the supporting surfaces of the conveyer sections to coincide with the predetermined plane of conveyance when in the position of maximum elevation, and since this position is always occupied by the forwardly-moving supporting surface of one or the other of the two sets of sections, the result is that the load being conveyed is propelled continuously forward by the alternating action of

said two sets of sections as described in my 65 prior Letters Patent above referred to.

The construction of conveying unit above described is reversible, that is to say, the conveying unit will be operative in either direction according to the direction in which 70 its driving shaft is rotated, and this is an advantage in many cases, though not always essential. It is to be understood, however, that my broad invention is not limited to this or any other specific construction of 75 the conveying units which are employed in my complete apparatus.

The conveying unit of which a portion only is shown in Figs. 1 and 2 has the same construction and mode of operation as the 80 complete unit already described, and the automatic transference of the load from one of these units to the other, or from any similar unit to the next in series, when thus constructed, is provided for by interleaving the 85 adjacent ends of the conveyer sections of each pair of consecutive units in such manner that the supporting surface of one unit will overlap the supporting surface of the other unit. In such case, assuming that the 90 consecutive units are operating simultaneously and in the same direction, when an object which is being conveyed reaches the end of one of the conveying units it will be located above one set or the other of the 95 conveyer sections of the next unit ahead at a time when said set of sections is in the depressed position, and when the latter sections rise and commence their forward movement the object will be deposited upon 100 them by the downward movement of the conveyer sections on which it has been resting and will be thence conveyed in a forward direction by means of the conveying unit on which it has just been deposited. 105 According to the construction represented in Fig. 2, the interleaving of the conveyer sections of the two units is accomplished by locating the conveyer sections of each unit at such a distance apart that the sections of the 110 other unit may enter and move freely within the spaces thereby provided, the conveyer sections of the two units being arranged in staggered relation. The extent of the interleaving of the conveyer sections will usually 115 depend upon the size of the objects intended to be conveyed, said conveyer sections being preferably overlapped to such an extent that the interleaved portion of the supporting surface of either unit will provide a sufficient support for the load, regardless of the positions occupied by the conveyer sections of the two units. This arrangement insures the transference of the load from one conveying unit to the next, even though 120 said units are operated otherwise than synchronously, as hereinafter explained.

In Fig. 2 I have shown in dotted lines a

portion of a stationary landing such as is preferably employed at each of the extreme ends of the complete apparatus, for the purpose of facilitating the transference of the load to and from the apparatus at these points. This landing consists essentially of a grating composed of a series of bars 41 rigidly secured together, side by side, but spaced apart sufficiently to receive freely between them the ends of the conveyer sections of the adjacent conveying unit, being arranged in staggered relation with respect to said conveyer sections and interleaved therewith to a suitable distance. These bars 41 are substantially equal in number to the conveyer sections; and their upper edges are all located in a plane parallel with but slightly below the plane occupied alternately by the supporting surfaces of the two sets of conveyer sections when the latter are in the position of maximum elevation. The graded landing thus provided is supported in any suitable manner and will usually form a continuation of a stationary platform, and in operation, assuming that the conveyer is bringing up a load toward the landing, this load will ultimately be supported by one set or the other of the conveyer sections at a point where the latter are interleaved with the stationary bars of the landing, whereupon when said conveyer sections move downward and backward the load will be deposited upon said bars, ready to be removed therefrom by an attendant. Conversely, an object which is placed upon the interleaved portions of the bars 41 will ultimately be picked up by one set or the other of the conveyer sections and will be thence conveyed away as above described. Whatever may be the particular construction or the number of the conveying units which are comprised in my apparatus, provision is made for actuating each conveying unit separately from or independently of the others, in the sense that the operation of each unit is or may be differentiated from that of every other unit with respect to one or more of such characteristics as its direction, time and speed. This individualization or capacity for independent operation of the units is a distinguishing feature of my present invention, broadly considered, and may be taken advantage of in a variety of ways and with various useful results. For example, provision may be made for starting and stopping each unit independently of all the others, in which case a given object, or as much of a load as can be placed upon a single conveying unit, may be transported from any given point in the length of the complete apparatus to any other given point by causing each conveying unit to operate only so long as the load is resting upon it, and to remain at rest at all other times, the conveying units being operated

sequentially. The transportation of the given object or load from one point to another may thus be effected without using for the purpose any more power than is required to operate one conveying unit only, or at most two adjacent conveying units in case the load rests partially on each of them while being transferred from one to the other, and I am thereby enabled to effect a great saving of power over what has been required for the operation of prior conveyers, all of which, so far as I am aware, have been so constructed that each of them must necessarily be operated as a whole and must therefore require the expenditure of sufficient power for that purpose, regardless of the size of the load conveyed. It is also possible to cause my apparatus to operate in one direction throughout one or more different portions of its length, and to operate simultaneously in the opposite direction throughout one or more other portions of its length, assuming that provision is made for reversing the several conveying units independently of one another. In such case the apparatus will serve to convey simultaneously a number of objects or individual loads from two separate points to a common point of distribution, or, conversely, to convey a number of objects or individual loads from any given point along the length of the apparatus to any two other points located in opposite directions therefrom.

For operating the several conveying units it will be found convenient in most cases to provide each unit with an electric motor and to connect all the motors in parallel circuit with the supply circuit which energizes them, in which case the operation of the apparatus may be controlled by means of suitable switches included in the branch circuits through the several motors. The conveying unit illustrated in Fig. 1 is provided with such a motor, indicated at 42, which motor is carried by the stationary framework of the apparatus, beneath the conveyer sections, and connected to the driving shaft 23 by means of gearing 43. I prefer to employ for this purpose a motor which will operate in either direction, according to the polarity of its circuit terminals, in which case the reversal of the direction of operation of the corresponding conveying unit, as well as the starting and stopping of the unit, can be provided for by employing a suitable pole-changing switch for controlling the circuit through the motor, similar motors and switches being employed for all the other conveying units. Such an arrangement is illustrated diagrammatically in Fig. 6, in which are shown a number of consecutive conveying units C each of which is assumed to be provided with a reversible motor controlled by

one of a corresponding series of pole-changing switches D. Except as hereinafter described, each of the switches represented in this figure is of a well-known type consisting of two parallel arms 44 each pivoted at one end to and insulated from a switchboard or other suitable support, in position to be moved into or out of contact with one or the other of a pair of insulated contact terminals 45 and 46. There are two of the terminals 45, one for each switch arm 44, while the other terminal 46 serves as such for both of the switch arms, being located between the terminals 45. The arms 44 are compelled to move in unison by means of an insulated link 47 pivoted thereto, which link also carries an operating handle 48, the arrangement being such that when the handle 48 is moved sufficiently in one direction one of the arms 44 will make contact with one of the outer terminals 45 and the other with the middle terminal 46, while when said handle is moved in the opposite direction that switch arm which was previously in contact with the terminal 46 will be brought into contact with the other outer terminal 45 and the other switch arm will simultaneously make contact with said terminal 46. The outer terminals 45 are electrically connected by a suitable conductor 49, and from the terminals 45 and 46 respectively the circuit wires 50 and 51 lead to the corresponding motor, either directly, or through a supplementary switch herein after described. The pivoted ends of the switch arms 44 are also electrically connected by conductors 52 and 53 to the main feed wires 54 and 55 respectively, the result of this arrangement being that when said switch arms are in either of their contact positions the motor will rotate and the corresponding conveying unit will operate in one direction or the other, which direction will be reversed when the switch arms are thrown into the other contact position, while when said switch arms are in an intermediate position, or out of contact with any of the terminals, the circuit through the motor will be broken and the motor and its conveying unit will remain at rest. Thus by operating the several switches D at the proper times and in the proper sequence the apparatus may be caused to convey a load or a series of loads from any given point along its length to any other such point, or to convey simultaneously one or more loads in one direction and one or more other loads in the opposite direction, without requiring in any case the expenditure of any more power than is necessary for driving those conveying units which are actually operative in supporting and conveying the load or loads.

Assuming that the arrangement of the parts represented in Fig. 6 is such that each

conveying unit will be operative in that direction toward which its switch has been thrown to close the circuit through the corresponding motor, it will be seen that this figure illustrates a situation in which the central conveying unit of the series indicated will be at rest, while the conveying units on both sides of said central unit will be operating toward the latter unit. In such case this temporarily-inoperative or idle unit will serve as a stationary landing to receive the loads brought up by the operative units from one or both directions, its conveyer sections being interleaved with the conveyer sections of both of the adjacent units and therefore constituting, in effect, the bars of a relatively fixed grating such as has been previously described. If all the switches corresponding to the operative units were thrown over to reverse the respective motors, then the apparatus would evidently operate to take up loads placed upon the end portion or portions of the idle unit and convey the same away in one or both directions. In either case, the presence of the idle unit permits an attendant to remove the loads therefrom as fast as they are brought up, or, conversely, to place the loads upon said unit in position to be removed therefrom by the adjacent units, without being inconvenienced in so doing by any movement of said idle unit. The presence of such a temporarily-inoperative unit is also desirable whenever two loads are to be conveyed to a common point from opposite directions, in order to prevent such loads from being thrown against each other at the meeting ends of two consecutive units, and I therefore prefer to provide means for so controlling the operation of the switches D that no two adjacent switches can be set to cause the corresponding units to operate toward each other. In the present instance this is accomplished by providing each of the switches with an arm 56 pivoted at its upper end to the switch board and carrying at its lower end a bar 57 which extends laterally therefrom in both directions, in the plane of movement of said arm, and is formed on an arc of a circle described from the point at which the arm 56 is pivoted to the switchboard. All of the bars 57 are located in the same plane, and each bar is of such length that when the switch arms 44 or any pair of adjacent switches are in their vertical or open-circuit position the adjacent ends of the corresponding bars 57 will be located just outside of the curved paths of movement of each other. Thus when any switch has been thrown into either one of its circuit-closing positions the bar 57 which is connected to and moves with said switch will be carried in front of the adjacent end of the similar bar carried by one of the next switches in the series, and

will therefore be located in such position as to form a stop or obstacle which will prevent the bar carried by the latter switch from being moved toward the first-mentioned 5 switch. This is clearly illustrated in Fig. 6, which shows a condition in which the central switch D is prevented from moving in either direction by reason of the fact that the bars 57 carried by the two adjacent 10 switches extend across the path of movement of the bar carried by said central switch, the conveying unit corresponding to this switch being thus caused to remain at rest. As thus constructed, any switch may 15 be thrown into its open-circuit position at any time, regardless of the position of any other switch, and all the switches may occupy at the same time either one of the closed-circuit positions, while any two adjacent 20 switches may also be moved at any time in such directions as to cause the corresponding units to operate away from each other, none of the bars 57 being effective as stops except when it is attempted to cause 25 two consecutive conveying units to operate toward each other, as will be evident.

The arrangement above described for controlling the operation of a series of switches is described and claimed in another application for United States Letters Patent filed 30 by me on the 29th day of January, 1907, Serial No. 354,702, and is not of itself claimed herein.

In order to render the conveyer as automatic in its action as possible and thereby minimize the personal attendance involved in operating the various switches or in otherwise controlling the operation of the several conveying units, I prefer to provide each 35 of the units with devices so constructed and arranged that the passage of an object onto and off a unit will automatically start and stop the same. This arrangement is particularly useful when a considerable number of 40 the units are to be operated consecutively in the same direction and are to be employed for conveying freight or baggage, since in such case the operation of the apparatus will be automatically controlled by the movement of the load itself throughout the entire 45 travel of the latter, after it has once been started, until its landing point is reached. An arrangement for this purpose is shown in the accompanying drawings in combination with the conveying unit illustrated in Figs. 1 to 5 inclusive, in which 50 58 represents a bar extending along the longitudinal center of the unit from one end to the other, or substantially so, and pivoted 55 to the upper ends of a pair of parallel arms 59, said arms being carried by transversely-extending rock shafts 60 located beneath the conveyer sections and journaled on the side beams 39. The arms 59 are of equal length 60 above their respective rock shafts, so that

the bar 58 is kept parallel with the conveyer sections in all positions of said parts, and one of said arms 59 is extended below the rock shaft which carries it, as at 61, and is provided at its lower end with a weight 62 70 which is sufficiently heavy to overbalance the bar 58 and thus tends to hold the arms 59 in vertical position and thereby maintain said bar in its position of maximum elevation, in which it is located somewhat above 75 the supporting surface of the conveying unit. From this position the bar 58 can move longitudinally in either direction, which movement will evidently carry it downward also, and a space is provided between two of 80 the conveyer sections for receiving said bar, so that when it has been moved to a sufficient extent in either direction its upper edge will be flush with the supporting surface of the conveying unit, to which end one of the 85 conveyer sections may be omitted, as shown in Fig. 5. As thus constructed, whenever an object such as a crate 63, for example, is resting on the conveying unit its weight will hold the bar 58 depressed and will thus 90 maintain the weight 62 at one or the other of its extreme positions, as shown in Fig. 1, but as soon as the crate or other object passes off the conveying unit the weight 62 will raise said bar into its elevated position. 95 When in this position the bar will be located in the path of any load which may be moving toward it along the conveyer, and as soon as such load is carried against either 100 end of said bar it will force the latter forward against the resistance offered by the weight 62 until the bar has been depressed sufficiently to allow the load to pass over it, whereupon it will remain depressed as above described so long as the load remains upon 105 the conveying unit. In Fig. 1 the crate 63 is assumed to be moving toward the right, having just left the conveying unit partially represented at the left hand end of said figure, so that the bar 58 on which the crate 110 is resting has been pushed toward the right by the crate and is now being held depressed by the weight of said crate, with the weight 62 at the left hand limit of its movement. If the crate had been moved onto the same 115 conveying unit from the opposite direction the bar 58 would have been pushed to the left and the weight 62 would occupy its extreme right hand position, the pivotally-mounted arms 59 being swung by an ap- 120 proaching load in one direction or the other according to the direction from which the load is brought up. The movements of the parts just described are utilized for controlling the driving of the shaft 23 in such manner as to cause the conveying unit to operate whenever a load is resting upon it and to remain at rest at all other times, this being accomplished in the present instance by 125 causing the weighted arm 59 to operate a 130

switch interposed in the circuit which includes the motor 42. This switch may be of any suitable type, being herein represented as comprising two metallic arms 64 and 65 which are insulated from each other and are pivoted at their upper ends to the under side of a housing 66 carried by the framework of the apparatus, beneath the conveyer sections. These arms are arranged 5 to swing in vertical planes, in parallelism with the weighted arm 59, to the extension 61 of which they are connected by a link 67 pivoted to the latter and to an insulating cross bar 68 which connects their free ends, 10 so that they swing in unison with said arm 59. At their pivoted ends said arms 64 and 65 are electrically connected respectively, through their pivots, to conductors 69 and 70 which lead to the terminals of the motor 15 42 which operates the conveying unit, and at the extremities of the swinging movement of said arms are located two corresponding sets of spring-jaw contacts 71 and 72, in position to receive the respective arms between their jaws. The contacts 71 and 72 20 are electrically connected in independent pairs as hereinafter described, and the respective pairs are connected in turn to the two branches of the supply circuit, as by 25 conductors 73 and 74 leading respectively to the circuit wires 50 and 51 which pertain to the corresponding switch D, the arrangement being such that when the weighted arm 59 is in its vertical position the switch 30 arms 64 and 65 will be out of engagement with any of the contacts 71 and 72, so that the circuit through the motor will be broken and the conveying unit will not operate, while when said weighted arm is in either 35 40 one of its extreme positions the switch arms will be engaged with one set or the other of said contacts and the circuit through the motor will therefore be closed and the conveying unit caused to operate.

45 Two methods of electrically connecting the contacts 71 and 72 in pairs are illustrated in the drawings. According to one method, which is shown in Fig. 7, the two contacts 71 are connected by a conductor 75 50 to form one pair and the two contacts 72 are connected by a conductor 76 to form the other pair, in which case the direction of rotation of the motor 42 will evidently be the same whether the switch arms 64 and 55 65 are in engagement with one or the other of the two sets of contacts and will be controlled by additional means such, for example, as one of the switches D. According to the method shown in Fig. 8 the diagonally- 60 opposite contacts 71 and 72 are connected by conductors 77 and 78, and with this arrangement the direction of operation of the motor and the conveying unit will be reversed whenever the switch arms are moved 65 from one of their extreme positions to the

other, so that if the circuit connections are properly arranged the conveying unit will be automatically caused to operate in the direction of movement of any load which sets it in motion.

70 It will be evident that the constructional features of the conveying unit herein described are applicable to conveyers which are not composed of independently-operated units, and certain of said features are described and claimed in another application for U. S. Letters Patent filed by me on the 25th day of July 1907 Serial No. 385,459 and are not claimed herein. It is also to be understood that the capacity of the conveying 75 units to be operated independently may be taken advantage of in various other ways than have been specifically described herein, and that many different arrangements may be employed for operating and controlling 80 the units without departing from my broad invention. For example, in Fig. 9 I have illustrated an arrangement in which the conveying units are differentiated from one another with respect to their speeds of 85 operation, for the purpose of enabling a load to be started at a slow speed at one end of the conveyer and to have its speed progressively increased until the desired maximum speed is attained and then progressively diminished until the other end of the conveyer is reached. This arrangement is particularly advantageous in many cases where the apparatus is designed to carry passengers for a considerable distance, for the 90 reason that it provides for taking on and depositing the passengers at a safe speed without preventing their conveyance from one end of the apparatus to the other at a high average speed. The arrangement 95 shown in Fig. 9 comprises a series of conveying units C constructed and interleaved at their ends as already described, the driving shaft 23 of each unit being connected, as by a pair of intermeshing gears 79 and 100 80, to a main shaft 81 which is common to all the units and is driven and controlled in any suitable manner. The gears constituting the several pairs are so proportioned that the conveying units at the ends of the 105 apparatus are driven at a relatively slow speed, which in practice will be such as to enable the load to be taken-up and deposited automatically, while the pairs of gears which drive the next to the end units in the series 110 115 are proportioned to give said units a speed which is somewhat greater than that of the end units, the difference between the speeds of the adjacent units being ordinarily equal, or approximately so, to the speed of the end 120 units. The speed of succeeding units in the series may be still further increased in like manner, while all the units located between the first and last units in the series which operate at the maximum speed are driven at 125 130

- the same speed as the latter units and will ordinarily include the greater part of the length of the apparatus, this portion of the apparatus being omitted from Fig. 9 for want of space. As thus constructed, a passenger, for example, will be taken up at one end of the apparatus at a safe speed by the end conveying unit, by which he will be transported at that speed until the next unit is reached, whereupon his speed will be increased by a suitable increment, and this progressive increase of his speed will continue until finally he will be transported along the central portion of the apparatus at the desired maximum speed. As soon as he reaches the end of this portion of the apparatus his speed will be progressively diminished as he is transferred successively to the last few conveying units of the apparatus, and he will finally be transported by the last unit at a speed which will permit him to step or be deposited upon a stationary landing without danger or inconvenience.
- 25 I claim as my invention:
1. A conveying apparatus comprising a series of reversible, separately-operated conveying units arranged end to end, means for starting, stopping and reversing said units independently of one another, and means for preventing consecutive units from operating toward each other.
  2. A conveying apparatus comprising a series of reversible, separately-operated conveying units arranged end to end, the supporting surfaces of consecutive units being overlapped at their adjacent ends, means for starting, stopping and reversing said units independently of one another, and means for preventing consecutive units from operating toward each other.
  3. A conveying apparatus comprising a series of independent, reversible conveying units arranged end to end, each unit being provided with a reversible electric motor for operating the same, a series of reversing switches for controlling the operation of the respective motors, and means operative with said switches for preventing consecutive units from operating toward each other.
  4. A conveying apparatus comprising a series of reversible, separately-operated conveying units arranged end to end, in combination with means operative with the passing of a load onto and off each unit in either direction for starting and stopping the same.
  5. A conveying apparatus comprising a series of independent conveying units arranged end to end, each unit being provided with an electric motor for operating the same, and means operative with the passing of a load onto and off each unit for closing and opening the circuit through the corresponding motor.

6. A conveying apparatus comprising a series of independent, reversible conveying units arranged end to end, each unit being provided with a reversible electric motor for operating the same, and means operative with the passing of load onto and off each unit in either direction for closing and opening the circuit through the corresponding motor.

7. The combination with a conveyer and means for actuating the same, of a bar extending lengthwise of said conveyer and mounted to move downward under the weight of a load deposited thereon, means for elevating said bar above the supporting surface of the conveyer, and means operative with the movements of said bar for controlling the operation of said conveyer.

8. A conveying apparatus comprising a series of separately-operated conveying units arranged end to end, each unit being provided with a bar extending lengthwise thereof and mounted to move downward under the weight of a load deposited thereon, means for elevating said bars above the supporting surfaces of the respective units, and means operative with the movements of each bar for controlling the operation of the corresponding unit.

9. The combination with a reversible conveyer and means for actuating the same, of a bar extending lengthwise thereof and mounted to move forward in either direction and downward, means for elevating said bar above the supporting surface of the conveyer, and means operative with the movements of said bar for controlling the operation of said conveyer.

10. The combination with a conveyer and an electric motor for actuating the same, of a bar extending lengthwise thereof and mounted to move downward under the weight of a load deposited thereon, means for elevating said bar above the supporting surface of the conveyer, a switch controlling the circuit through said motor, and connections between said bar and switch for operating the latter.

11. The combination with a conveyer and means for actuating the same, of a bar extending lengthwise thereof and supported on the upper ends of parallel arms mounted to rock in either direction, means tending to maintain said arms in their position of maximum elevation, and means connected thereto for controlling the operation of the conveyer.

12. The combination with a conveyer comprising sets of interleaved and laterally-adjacent conveyer sections and means for actuating the same to impart a forward movement to a load supported thereon, of a bar extending lengthwise of said sections, in parallelism therewith, and mounted to move downward between said sections under

the weight of the load, means for elevating said bar above the supporting surfaces of said sections, and means operative with the movements of said bar for controlling the 5 operation of the conveyer.

13. A conveying apparatus comprising a series of separately-operated conveying units arranged end to end, each unit being provided with a bar extending lengthwise thereof and mounted to move downward under the weight of a load deposited thereon, means for elevating said bars above the supporting surfaces of the respective units, and means operative with the movements 15 of each bar for controlling the operation of the corresponding unit.

14. A conveying apparatus comprising a series of reversible, separately-operated conveying units arranged end to end, each unit being provided with a bar extending lengthwise thereof and mounted to move forward in either direction and downward, means for elevating said bars above the supporting surfaces of the respective units, and means 25 operative with the movements of each bar for controlling the operation of the corresponding unit.

15. A conveying apparatus comprising a series of independent conveying units arranged end to end, each unit being provided with an electric motor for operating the same and with a bar extending lengthwise of the unit and mounted to move downward under the weight of a load deposited 35 thereon, means for elevating said bars above the supporting surfaces of the respective units, and a switch connected to each bar and arranged to control the circuit through the corresponding motor.

40 16. A conveying apparatus comprising a series of separately-operated conveying units arranged end to end, each unit being composed of sets of interleaved and laterally-adjacent conveyer sections and provided 45 with means for cyclically actuating the same to impart a forward movement to a load supported thereon, a bar extending lengthwise of each unit and mounted to move downward between the conveyer sections 50 thereof, means for elevating said bars above the supporting surfaces of the respective units, and means operative with the movements of each bar for controlling the operation of the corresponding unit.

55 17. A conveying apparatus comprising a series of independent conveying units arranged end to end, each unit being composed of sets of interleaved and laterally-adjacent conveyer sections, and provided with means 60 including an electric motor for cyclically actuating said sections to impart a forward movement to a load supported thereon, a bar

extending lengthwise of each unit and mounted to move downward between the conveyer sections thereof, means for elevating 65 said bars above the supporting surfaces of the respective units, and a switch connected to each bar and arranged to control the circuit through the corresponding motor.

18. A conveying apparatus comprising a series of independent conveying units arranged end to end and each including sets of interleaved and laterally-adjacent conveyer sections, both sets of sections in each unit being interleaved at their ends with 75 both sets of sections in the adjacent unit or units, and means for cyclically actuating the sets of sections to impart a forward movement to a load supported thereon.

19. A conveying apparatus comprising a series of independent, reversible conveying units arranged end to end and each including sets of interleaved and laterally-adjacent conveyer sections, both sets of sections in each unit being interleaved at their ends 85 with both sets of sections in the adjacent unit or units, and means for cyclically actuating the sets of sections to impart a forward movement in either direction to a load supported thereon. 90

20. A conveying apparatus comprising a series of independent conveying units arranged end to end and each including sets of interleaved and laterally-adjacent conveyer sections, both sets of sections in each 95 unit being interleaved at their ends with both sets of sections in the adjacent unit or units, means including a motor for each unit for cyclically actuating the sets of sections to impart a forward movement to a load 100 supported thereon, and means for starting and stopping any motor independently of the other motors.

21. A conveying apparatus comprising a series of independent, reversible conveying units arranged end to end and each including sets of interleaved and laterally-adjacent conveyer sections, both sets of sections in each unit being interleaved at their ends 105 with both sets of sections in the adjacent unit or units, means including a reversible motor for each unit for cyclically actuating the sets of sections to impart a forward movement in either direction to a load supported thereon, and means for starting, stopping and reversing any motor independently 110 of the other motors. 115

In testimony whereof, I have hereunto subscribed my name this twelfth day of April, 1907.

PIERRE LORILLARD.
